UNITED STATES PATENT OFFICE.

WILLIAM H. VOSS, OF DAVENPORT, IOWA.

MEANS FOR OPERATING WASHING-MACHINE WRINGERS.

1,004,607.

Specification of Letters Patent.

Patented Oct. 3, 1911.

Application filed August 25, 1909. Serial No. 514,585.

To all whom it may concern:

Be it known that I, WILLIAM H. Voss, a citizen of the United States, residing at Davenport, in the county of Scott and State 5 of Iowa, have invented new and useful Improvements in Means for Operating Washing-Machine Wringers, of which the following is a full, clear, and exact description.

My invention relates to means for operating 10 washing machines and wringers, and particularly the type or class of washing machines having a rotary reciprocal agitator and a momentum or balance-wheel to assist in the reversal movement of agitator, the 15 same being adapted to be either driven by hand or by means of a suitable motor.

In operating a wringer by means of a motor, it has often occurred that the fingers of the operator became caught in the rollers 20 thereof and crushed, or buttons on the clothing being wrung are broken by being carelessly fed through the machine.

It is, therefore, an object of this invention to avoid these very objectionable features by 25 connecting the wringer with the motor by suitable mechanism that will instantly stop the operation of the wringer while the motor will continue to rotate. These elements are so arranged that the instantaneous stopping 30 of the wringer will not burn out or "kill" the motor.

Still another object of my invention is to connect up the mechanism so that either the agitator or the wringer may be operated independently of the other, and also to provide 35 means whereby it is possible to throw the wringer into or out of operation by a foot-treadle, so that both hands of the operator may be free to feed the clothes to the rollers.

40 I accomplish the above objects by the means and in the manner hereinafter fully described and as more particularly pointed out in the claims, reference being had to the accompanying drawings, forming a part 45 hereof, wherein,

Figure 1 is a vertical side elevation of my improved device looking at the same from the side of the tub on which the balance-wheel and motor are mounted. Fig. 2 is a 50 vertical side elevation looking at the same from the diametrically opposite side of the tub and showing said tub, etc., in dotted lines for the purpose of illustrating the operation of the foot-treadle and its asso-

ciated parts. Fig. 3 is a horizontal section 55 taken just below the plane of the bottom of the tub for the purpose of illustrating the location and arrangement of the various parts of the machine below the tub. Fig. 4 is a central longitudinal section of the clutch 60 that is utilized for disconnecting the balance-wheel from its shaft and transforming said balance-wheel into an idler.

My invention, as shown in the drawings, is applied to a washing machine comprising 65 a tub or body, A, which is supported by legs a, a the latter being connected by diagonally arranged metal cross-braces a', a'; and means, B, for converting and transmitting the reciprocal movement of a horizontally 70 disposed rack, C, to the usual rotary reciprocal agitator located within the tub. It is immaterial in what manner the means, B, are constructed, or of what mechanism the same consist, in so far as the objects sought 75 to be accomplished by my improvements are concerned. I prefer, however, to employ for this purpose a small horizontally disposed gear or pinion mounted to revolve with the agitator shaft, but so arranged as 80 to permit of the free longitudinal movement of the latter therein. This mechanism is preferably supported on the lid or cover closing the top of the tub and inclosed within a suitable spherical casing, substan- 85 tially as shown.

The rack, C, extends horizontally and transversely across the lid to a point beyond the side of the tub, and has its outer end removably pivoted between lugs projecting 90 from a socket made integral with the upper end of a vertically disposed lever, D, of the second class. This lever is fulcrumed between the bifurcations of a bracket e, secured to and projecting from the side of the 95 tub, substantially as shown, and has a handle inserted in the socket in its upper end, while one end of a pitman 2 is pivotally connected to its lower end. This pitman 2 extends to and under the tub of the machine, and its 100 opposite end is pivotally connected to a comparatively large gear 3, that engages a pinion 4. The shaft on one end of which gear 3 is secured, is journaled in suitable bearings near one end of a cross-bar 5, extending between two of the legs of the tub of the machine. A suitable bearing for a horizontal shaft 6, on which the pinion 4

is mounted, is secured to this cross-bar 5 adjacent the leg of the tub, substantially parallel to said first mentioned bearing, and this shaft 6 extends beyond the side of the 5 tub where the fly-wheel 7 is securely mounted thereon. Fly-wheel 7 is provided with a circumferential groove 8 and is driven through the medium of a belt 9 that connects it with a small grooved pulley 10 10 on the outer end of the armature-shaft of an electric motor 11.

The base of motor 11 is bolted or otherwise removably secured to the platform of a stand 12, which has its end nearest the 15 machine preferably bifurcated and hinged to the adjacent extended end of a horizontal rod 13 having bearings in suitable brackets 14 that are secured to and project from the adjacent legs of the tub. The opposite free 20 end of stand 12 is supported by means of a leg, thus insuring a solid foundation for the motor at all times, as well as, providing convenient means whereby the same may be readily disassembled when the machine is 25 "knocked-down" for shipment.

Secured to the upper edge of the tub is a suitable wringer drip board 15 preferably of cast metal, having a vertical plate or wall extending along its outer longitudinal 30 edge. A wringer 16, of any suitable or well-known type, is clamped to this vertical wall and has the shaft 17, on which its driving roller is mounted, extended a distance beyond its bearings and provided with a 35 large pulley 18. This pulley is preferably connected by means of a loose belt 19 with a small pulley 20 that is fast on the inner boss of the balance-wheel 7 and is adapted to be thrown into or out of operation by 40 means of an idle take-up pulley 21. Said pulley adjusts the slack in belt 19 by the oscillation of its journal which comprises a lateral L-shaped extension 22 of a horizontally disposed rock-shaft 23, the latter 45 being preferably elongated so that it extends transversely across and in a plane parallel with the bottom of the tub, and is journaled in bearings 24, 24, secured to the adjacent legs of said tub. A suitable arm 50 is firmly secured to and projects rearwardly from the extended end of rock-shaft 23 opposite the L-shaped extension 22, and this arm is connected by a suitable link 26 to the outer free end of a horizontally disposed foot-treadle 27, the latter being fulcrumed on a pivotal stud 28 secured to and projecting from one of the cross-braces a'. The arrangement of the parts just described is such that when the treadle 27 is de- 55 pressed the extension 21 on the opposite end of the rock-shaft 23 will be moved toward and tighten the belt 19 on pulleys 18 and 20, so that the wringer will thus be driven by means of the motor.

60 It is desirable that the wringer should be

operated independent of agitator mechanism and therefore the balance-wheel should be disconnected from its shaft and made to revolve as an idler, for which purpose I have devised a clutch such as is illustrated in 70 Fig. 4 of the drawings. In this view it will be seen that shaft 6 extends beyond its bearings a suitable distance and has the balance-wheel 7 mounted loosely thereon near its outer end. The outer face of the 75 boss of the balance-wheel is provided with one or more laterally disposed lugs 29 that are adapted to be seated in corresponding grooves or recesses 30 made in the adjacent edge of a longitudinally slideable sleeve 31 on 80 the outer end of said shaft. This sleeve is preferably bored out wider than the diameter of shaft 6 to a point near its inner end where it is reduced in diameter and forms a shoulder 32. The outer portion of this 85 bore is preferably closed between the shaft and sleeve by a suitable bushing 33 fast on shaft 6 between which latter and said shoulder 32 a coiled expansion spring 34 is placed so as to surround said shaft. This 90 keeps the sleeve normally pressed toward the balance-wheel and locks the parts together so that they will all revolve with the shaft. The pin 35 that secures the bushing 33 to the shaft extends through and operates in an L-shaped bayonet-slot 36 cut on opposite sides of the sleeve 31. Thus, when it is desired to release the balance-wheel 95 from its shaft for the purpose of using it as an idler, it is necessary to simply move the 100 sleeve 31 outwardly on the shaft and away from the balance-wheel until the lugs 29 are withdrawn from grooves 30 in said sleeve, and then rotate said sleeve slightly 105 so that the pin 35 will seat in the lateral portion of the slot 36. The shaft will then remain stationary and the wringer may be driven by the motor independent of the 110 agitator mechanism.

When it is desired to operate the washing machine mechanism by the motor 11, the high speed of the small armature pulley 10 is imparted through belt 9, to the much larger fly-wheel 7, and reduced thereby, and this reduced motion is transmitted through the medium of the fly-wheel shaft 6 and pinion 4 on the opposite end thereof, to the large gear 3 by which said motion is further reduced. This reduction of the motion increases the effective power of the motor 115 and by means of pitman 2, the lever D is rocked back and forth and rack C reciprocated and the agitator within the machine is thus actuated. When it is desired to operate the machine by hand, the belt 9, connecting the motor and fly-wheel can be easily disconnected and removed, simply by elevating the stand 12, so as to slacken or remove the belt. The operator then 120 grasps the handle and drawing it back and 125 130

forth actuates the agitator through the medium of the rack C, and at the same time revolving gear 3, through the medium of the pitman 2. The engagement of the latter with pinion 4, imparts a very high speed to the shaft 6 and fly-wheel 7, and the momentum of the increased motion of the latter, by virtue of the energy due to its acquired inertia greatly assists the operator 5 in working the machine. The same means that operate the reversing mechanism of the washing machine may be employed to operate the wringer when it is desired to dispense with the motor and turn the latter 10 by hand. It is preferred that the wringer be disconnected from the reversing mechanism and the balance-wheel utilized as an idler by throwing out the clutch. Thus the operator standing on the treadle side of the 15 tub depresses the same by his foot and tightens the belt 19 on the pulleys 18 and 20, and said wringer is then driven by the motor independent of the reversing mechanism. Should an accident occur the foot 20 treadle is allowed to raise thus loosening the belt 19 and instantly stopping the rotation of the wringer.

While I have described and illustrated particular means for carrying out my invention, I do not desire to be limited to these 30 specific constructions, as obvious changes may be made in the same without departing from the spirit of my invention.

What I claim as new is:—

35 1. Actuating mechanism for a wringer comprising a suitable support having legs, a shaft journaled below said support, a balance-wheel mounted loosely on said shaft, a clutch connecting said balance-wheel and shaft, means fulcrumed on the side of said support through the medium of which said balance-wheel is actuated, an independent shaft having bearings on said support, a pulley on said independent shaft, a belt engaging said wheel and pulley, an idler intermediate said first-mentioned pulley and balance-wheel, and means fulcrumed on one of said legs for moving said idler into and out of engagement with said belt.

40 2. Actuating mechanism for a wringer comprising a suitable support having legs, a shaft journaled below said support, a balance-wheel mounted loosely on said shaft, a clutch connecting said balance-wheel and shaft, a lever fulcrumed on the side of said support through the medium of which said balance-wheel is actuated, an independent shaft having bearings on said support, a pulley on said independent shaft, a belt engaging said wheel and pulley, an idler intermediate said first-mentioned pulley and balance-wheel, and means fulcrumed on one of said legs for moving said idler into and out of engagement with said belt.

45 3. Actuating mechanism for a wringer comprising a suitable support having legs, a shaft journaled below said support, a balance-wheel mounted loosely on said shaft, a clutch connecting said balance-wheel and shaft, a lever fulcrumed on the side of said support through the medium of which said balance-wheel is actuated, an independent shaft having bearings on said support, a pulley on said independent shaft, a belt engaging said wheel and pulley, an idler intermediate said first-mentioned pulley and balance-wheel, and means fulcrumed on one of said legs for moving said idler into and out of engagement with said belt.

50 4. Actuating mechanism for a wringer comprising a suitable support having legs, a shaft journaled below said support, a balance-wheel mounted loosely on said shaft, a clutch connecting said balance-wheel and shaft, a lever fulcrumed on the side of said support through the medium of which said balance-wheel is actuated, an independent shaft having bearings on said support, a pulley on said independent shaft, a belt engaging said wheel and pulley, an idler intermediate said first-mentioned pulley and balance-wheel, and means fulcrumed on one of said legs for moving said idler into and out of engagement with said belt.

55 5. Actuating mechanism for a wringer comprising a suitable support having legs, a motor-driven balance-wheel journaled below said support, a pulley journaled above said support, a belt connecting said pulley and wheel, an idler adapted to engage said belt, a rock-shaft having bearings on said support and having a lateral extension on which said idler is journaled, and a foot-treadle fulcrumed adjacent one end to one of said legs and adapted to rock said shaft and move said idler into and out of engagement with said belt and thereby connect and disconnect said wheel and first-mentioned pulley.

60 6. Actuating mechanism for a wringer comprising a suitable support having legs, a motor-driven balance-wheel journaled below said support, a pulley journaled above said support, a normally loose belt connecting said pulley and wheel, an idler adapted to engage said belt, a rock-shaft having bearings on said support and having an L-shaped extension on the lateral member of which

said legs for rocking said latter shaft and moving said idler toward and away from said belt for connecting and disconnecting said wheel and first-mentioned pulley.

3. Actuating mechanism for a wringer 70 comprising a suitable support having legs, a shaft journaled below said support, a balance-wheel mounted loosely on said shaft, a clutch connecting said balance-wheel and shaft, a lever fulcrumed on the side of said support through the medium of which said balance-wheel is actuated, an independent shaft having bearings on said support, a pulley on said independent shaft, a belt engaging said wheel and pulley, an idler intermediate said first-mentioned pulley and balance-wheel, a rock-shaft having bearings on said support and having a lateral extension on which said idler is journaled for moving said idler toward and away from said belt 75 for connecting and disconnecting said wheel and first-mentioned pulley, and a foot-treadle fulcrumed on one of said legs for rocking said latter shaft.

4. Actuating mechanism for a wringer 90 comprising a suitable support, a shaft journaled below said support, a balance-wheel mounted loosely on said shaft, a clutch connecting said balance-wheel and shaft, a lever fulcrumed on the side of said support through the medium of which said balance-wheel is actuated, an independent shaft having bearings on said support, a pulley on said independent shaft, a belt engaging said wheel and pulley, an idler intermediate said first-mentioned pulley and balance-wheel, and laterally movable means having bearings on said support for moving said idler into and out of engagement with said belt and thereby connecting and disconnecting 100 said wheel and first-mentioned pulley.

5. Actuating mechanism for a wringer 105 comprising a suitable support having legs, a motor-driven balance-wheel journaled below said support, a pulley journaled above said support, a belt connecting said pulley and wheel, an idler adapted to engage said belt, a rock-shaft having bearings on said support and having a lateral extension on which said idler is journaled, and a foot-treadle 110 fulcrumed adjacent one end to one of said legs and adapted to rock said shaft and move said idler into and out of engagement with said belt and thereby connect and disconnect said wheel and first-mentioned pulley.

6. Actuating mechanism for a wringer 115 comprising a suitable support having legs, a motor-driven balance-wheel journaled below said support, a pulley journaled above said support, a normally loose belt connecting said pulley and wheel, an idler adapted to engage said belt, a rock-shaft having bearings on said support and having an L-shaped extension on the lateral member of which

said idler is journaled, and a foot-treadle fulcrumed to one of said legs and connected to an off-set on the opposite end of said rock-shaft, the depression of which treadle moves
5 said idler against said belt and tightens the same and thereby connects and disconnects said wheel and first-mentioned pulley.

In witness whereof I have hereunto set my hand this 17th day of August 1909.

WILLIAM H. VOSS.
